UNITED STATES PATENT OFFICE.

WILLIAM H. CRESS, OF PHILADELPHIA, PENNSYLVANIA.

MOTOR-CYCLE.

No. 833,584.

Specification of Letters Patent.

Patented Oct. 16, 1906.

Application filed November 22, 1905. Serial No. 288,585.

To all whom it may concern:

Be it known that I, WILLIAM H. CRESS, a citizen of the United States, residing at Philadelphia, county of Philadelphia, and State of Pennsylvania, have invented a certain new and useful Improvement in Motor-Cycles, of which the following is a specification.

My invention relates to new and useful improvements in motor-cycles, and has for its object to provide an exceedingly simple and effective construction which will enable the rider to throw the cranks out of action and bring both pedals to their lowest point, where they may remain while the engine is in operation, thus giving a convenient rest for the feet of the rider, while maintaining the legs and body in a natural position and by means of which the rider may stand erect to relieve the body of shock and jars incident to traveling over a rough road-bed.

A further object of my invention is to put all of the operating mechanism under the control of the rider upon the handle-bars, so that the pedals may be thrown out of action, the cranks of the sparker advanced or retarded and the back pressure without removing the hands from the handle-bars, thus at all times giving the rider perfect control of the machine.

With these ends in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, forming a part of this specification, in which—

Figure 1 is a side elevation of a motor-cycle having my improvements applied thereto; Fig. 2, a section of the fly-wheel casing and crank-disks; Fig. 3, a section at the line $z-z$ of Fig. 2.

Referring to the drawings, A represents the frame of the machine, which may be of any ordinary construction, and to this frame is secured the engine B, the latter being bolted or otherwise secured to the fly-wheel casing C, which latter is formed with the frame or may be brazed thereto, as found best.

The two fly-wheels D are connected by the

crank E, to which the connecting-rod F is attached, the upper end of the latter being connected to the piston of the engine in the usual manner, and these fly-wheels D have formed therewith the shafts G, which are journaled in the casing C, as clearly shown in Fig. 2. One of the shafts G has secured thereon the sprocket-wheel H, around which the chain I is adapted to run, said chain also running around a suitable sprocket-wheel J, secured to the rear wheel of the machine, so that when the engine is operated the vehicle will be propelled.

K' represents disks having internal gears formed therein, and these disks are journaled upon the shafts G so as to revolve concentric therewith, and to each of the disks is attached a crank L, carrying suitable pedals M.

A shaft N is journaled in the casing and has secured upon one end the pinion O, which meshes with the internal gear of the disk K', while on the opposite end of this shaft is fitted a similar pinion O', which is free to revolve upon the shaft N, and this last-named pinion meshes with the internal gear of the disk K.

A clutch P is splined upon the shaft N and adapted to be thrown into or out of engagement with the pinion O', so as to cause the latter to revolve with the shaft N or leave it free to revolve independent of said shaft.

A clutch-lever Q is pivoted to the casing and engages with the clutch so as to control the sliding movements of the same, and the outer end of this lever has attached thereto the wire or cable R, which leads from suitable pulleys to the bell-crank lever S, the latter being pivoted to the head of the machine and connected with the hand-lever T, which extends into easy reach of the rider when grasping the handle-bar.

Thus it will be seen that when the machine is to be started the clutch is thrown into engagement with the pinion O', thereby becoming rigid with the shaft N, which will cause the two disks K and K' to revolve in unison on account of the pinions O and O' meshing with the internal gears of said disks, thus so connecting the cranks to cause them to revolve in unison, and as the rider is supposed to have one of the cranks to its highest point while the other remains at its lowest point before throwing the clutch into engagement with the pinion O' the action of the cranks

will be the same as in an ordinary bicycle. After the engine has been put into operation the throwing of the clutch P out of engagement with the pinion O', as before described, 5 will disconnect the two crank-disks so that they may be revolved separate from each other, thus allowing both pedals to be brought to their lowest position to act as a rest for the feet of the rider and to be utilized by him 10 for standing erect when occasion requires. Power is transmitted from the disks K and K' to the engine-shafts G, and consequently the fly-wheels, by train of gears U, journaled upon the frame C, the outer member of said 15 train meshing with the internal gear of the disk K, while the inner member of said train meshes with the gear V, secured upon one of the shafts G, so that when the crank-disks are revolved, as before described, power will 20 be transmitted to the fly-wheels, thus giving the engine its initial movements for the purpose of starting the same, as is well understood in the use of gasolene-engines. A suitable clutch mechanism of the ordinary construction 25 is arranged between the gear V and the shaft G, so that the engine when running will not revolve the disks K and K'; but when the latter are revolved they will effect the revolving of the fly-wheels D, and consequently 30 the actuation of the engine.

W represents a small gear-wheel fitted to revolve upon a stud secured to the casing C, this gear meshing with the internal gear of the disk K, and the hub of this gear has 35 formed thereon a cam a, adapted to act upon the sparking lever b, so as to make and break the circuit in connection with the pin d. This making and breaking of the electric circuit is for the purpose of producing the ignition 40 spark for operating the engine, as will be well understood.

To recede or advance the sparking, a suitable wire e is connected with the pin d and passing through suitable pulleys is connected 45 with the hand-lever f in easy reach of the hand of the rider in grasping the handle-bars, so that by the operation of this lever f the pin may be thrown backward. A suitable spring is intended to carry it forward, thus enabling 50 the rider to regulate the time of the spark.

In starting a gas-engine it is usually necessary to relieve the back pressure in order that the engine may operate from the cranks of the machine, and for this purpose I provide 55 relief-valve g at the top of the engine-cylinder and connect this valve by the wire h to the lever i, located in easy reach of the rider when holding the handle-bars, so that this valve may be opened for relieving back 60 pressure while the engine is being started and then closed for maintaining the compression after the engine is in operation.

In practice I prefer that the disks K and K' be fitted to run upon the ball-bearings l, so as 65 to reduce the friction thereof. These ball-

bearings may or may not be used, as best suits the requirements of the particular design of the machine.

Having thus fully described my invention, what I claim as new and useful is—

1. In combination with a motor-cycle, a casing, two shafts carried in said casing, a fly-wheel carried by each of said shafts, a crank connecting the two fly-wheels, a sprocket-wheel carried by one of the shafts 75 for transmitting power to the rear wheel of the machine through a suitable chain, two disks journaled concentric with the shafts, each of said disks being provided with internal gears, a shaft N extending across the 80 frame and journaled therein, a pinion carried rigidly upon one end of the shaft N and meshing with the internal gear of one of the disks, a second pinion to revolve upon the other end of the shaft N and meshing with the internal gear of the other disk, a clutch 85 splined to the shaft N adapted to be thrown into or out of engagement with the loose pinion whereby the two disks may be caused to revolve in unison or permitted to revolve independent of each other, a gear-wheel V secured upon one of the first-named shafts, a train of gears meshing with the internal gear of one of the disks and also with the last-named gear, and means for controlling the 90 clutch from the handle-bar of the machine, as specified.

2. In combination with a motor-cycle, a casing, two shafts carried in said casing, a fly-wheel carried by each of said shafts, a crank connecting the two fly-wheels, a sprocket-wheel carried by one of the shafts 100 for transmitting power to the rear wheel of the machine through a suitable chain, two disks journaled concentric with the shafts 105 each of said disks being provided with internal gears, a shaft N extending across the frame and journaled therein, a pinion carried rigidly upon one end of the shaft N and meshing with the internal gear of one of the 110 disks, a second pinion to revolve upon the other end of the shaft N and meshing with the internal gear of the other disk, a clutch splined to the shaft N adapted to be thrown into or out of engagement with the loose pinion whereby the two disks may be caused to revolve in unison or permitted to revolve independent of each other, a gear-wheel V secured upon one of the first-named shafts, a train of gears meshing with the internal gear 115 of one of the disks and also with the last-named gear, means for controlling the clutch from the handle-bar of the machine, a relief-valve located at the top of the engine-cylinder and means for controlling said relief-valve from the handle-bar of the machine, as specified.

3. In combination with a motor-cycle, a casing, two shafts carried in said casing, a fly-wheel carried by each of said shafts, a 130

crank connecting the two fly-wheels, a sprocket-wheel carried by one of the shafts for transmitting power to the rear wheel of the machine through a suitable chain, two disks journaled concentric with the shafts each of said disks being provided with internal gears, a shaft N extending across the frame and journaled therein, a pinion carried rigidly upon one end of the shaft N and meshing with the internal gear of one of the disks, a second pinion to revolve upon the other end of the shaft N and meshing with the internal gear of the other disk, a clutch splined to the shaft N adapted to be thrown into or out of engagement with the loose pinion whereby the two disks may be caused to revolve in unison or permitted to revolve independent of each other, a gear-wheel V secured upon one of the first-named shafts, a train of gears meshing with the internal gear of one of the disks and also with the last-

named gear, means for controlling the clutch from the handle-bar of the machine, a relief-valve located at the top of the engine-cylinder, means for controlling said relief-valve 25 from the handle-bar of the machine, a gear-wheel W meshing with the internal gear of one of the disks, a cam formed upon the hub of the last-named gear-wheel, a sparking lever adapted to be actuated by said cam, a 30 spring-actuated pin with which said lever is adapted to contact, and means controlling from the handle-bar of the machine for moving said pin to or from the sparking lever, as specified.

In testimony whereof I have hereunto affixed my signature in the presence of two subscribing witnesses.

WILLIAM H. CRESS.
